A. E. GREENE

ELECTRODE MECHANISM FOR ELECTRIC FURNACES

Filed Oct. 23, 1923

Fig. 2. INVENTOR

A. E. Greene

UNITED STATES PATENT OFFICE.

ALBERT E. GREENE, OF MEDINA, NEAR SEATTLE, WASHINGTON.

ELECTRODE MECHANISM FOR ELECTRIC FURNACES.

Application filed October 23, 1923. Serial No. 670,285.

My present invention is a continuation in part of my application for patent, Serial No. 279,776, filed February 28, 1919.

My present invention relates to electrode 5 cranes and to electrode holders for electric furnaces.

My previous application above referred to described my improvements embodying the use of vertical I-beams for supporting electrode 10 holders. My present invention relates more particularly to vertically placed I-beams carrying electrode holders at their upper end and providing means of raising or lowering the I-beam in engagement with 15 suitable rollers instead of moving the rollers along the vertical I-beam.

I have found it advantageous to mount a vertical I-beam so it can move vertically along its own axis and at the same time raise 20 and lower an electrode mounted on an arm attached to its upper end. In this way I am able to construct a very simple supporting arm for the electrode clamp and am also able to mount the cables carrying the current 25 to the electrode arm and in this way avoid having the conductors near the webs of the I-beams. In this way I am able to get a higher power factor than is possible when the cables are carried close to the supporting I-beam.

One feature of my invention relates to the construction of guide rollers which serve to keep the vertical I-beam in alignment.

In one modification my invention embodies the use of a suitable clamp at the upper end of the vertical I-beam, which clamp serves to carry a horizontal arm for supporting an electrode. This arm may either be a pipe or it may be any other suitable 35 structural member sufficiently strong to carry the weight of the electrode and the electrode holder at its outer end. This arm may extend beyond the I-beam on the side opposite the electrode and may serve to support insulators which carry the conductors 40 for the current to the electrode.

In one modification my invention contemplates a worm geared hoist mounted back of the I-beams and attached to the frame 45 work of the furnace, this worm gear hoist having a cable which operates on sheave wheels attached to the lower end of the I-beam serving to raise and lower the latter. These and other features of my present in-

vention will be further described in reference to the annexed drawings.

In the drawings Fig. 1 is an elevation view of the electrode crane embodying my present invention; Fig. 2 is a plan view showing three electrode holders diagrammatically to illustrate the arrangement of I-beams and electrode holder arms and conductors; Fig. 3 is a plan view of one modification of my invention showing the method of keeping the vertical I-beam in alignment; Fig. 4 is an elevation view of a channel shaped vertically placed beam serving as an electrode crane mast in accordance with my invention and showing rollers at the sides of it for keeping it in alignment; Fig. 5 is a plan view section of the channel shaped beam shown in Fig. 4; Fig. 6 is an elevation view of another type of vertical beam crane embodying my present invention; Fig. 7 is a plan view of the beam shown in Fig. 6.

Referring to Fig. 1 I have shown here a rolling cylinder furnace indicated at 1 with a spout 2 mounted on a supporting rail 3 on which it may be rolled to pour the molten charge out of the spout.

The electrode crane structure consists of a vertical I-beam 4 which is mounted between rollers 5 and 6 and is supported on a cable 7 which operates under sheaves 8 and 9, the cable being wound up on a drum 10 on the worm gear 11. The worm gear 11 is mounted on a suitable structural frame 12 which is attached to the furnace shell. The worm gear may be operated by hand wheel 13 or by gears connecting it with the motor which could be mounted underneath the structural frame supporting the worm gear. I have shown two members 14 and 15 which carry the guide rollers 5 and 6. I also have shown other rollers 16 and 17 which may be adjusted to prevent the I-beams from moving out of alignment away from either of the guide rollers 5 and 6. These rollers 15 and 16 may be made adjustable in accordance with my invention in my application for patent Serial No. 623,036, filed March 5, 1923.

I may also further accomplish the alignment of the vertical I-beam by placing the sheave 9 at a greater distance from the I-beam than the sheave 8 whereby an upward pull on the supporting cable will tend to

keep the back flange of the I-beam against the roller 6, thus when the electrode is lowered until it rests on the charge there will be no tendency for the vertical I-beam to change its position owing to the pressure of the electrode on the charge and this fact prevents the breaking of the nipple joints between the electrodes.

Instead of using rollers which press against the front and back surfaces of the I-beam I may mount rollers to press against the corresponding inner surfaces of the flanges of the I-beam as is illustrated in my application for patent, Serial No. 279,776.

In Fig. 1 I have shown the rollers 5 and 6 having flanges which serve to keep the vertical I-beam in alignment and prevent its movement in either direction parallel to the axis of these rollers. In Fig. 3 I have shown another method of keeping the I-beams in alignment.

Referring to Fig. 3, instead of using front and back rollers with flanges as shown at 5 and 6 in Fig. 1 I may provide front and back rollers 31 and 32 against which the I-beam 33 presses, these rollers being located at different elevations. The weight of the arm extending out on the side of roller 31 would press the I-beam against the roller 31 which roller is located above the roller 32 and the weight of the electrode on the arm would also press the I-beam against the lower roller 32. I have also shown rollers 34 and 35 which may be mounted so as to adjust the clearance between them and the flanges of the I-beam. By mounting two sets of these rollers 34 and 35, one set above the other, I am able to adjust the vertical alignment of the I-beam as it moves in the line parallel to its axis. These rollers 34 and 35 may be mounted eccentrically so that the clearance may be easily adjusted by turning the eccentric axes of these rollers.

Referring now to Fig. 1 I have shown a clamp 17 at the top of the I-beam 4 and an arm 18 which here I have shown as a pipe. This pipe may be made of extra strong construction in order to carry the weight of the electrode on its outer end. This may be mounted in the clamp 17 which can be bolted to go around it and therefore its position can be adjusted in order to move the electrode further out or nearer to the axis of the I-beam. The electrode is shown at 19 held in a suitable clamp 20 mounted in a clamping bracket 21, this latter being insulated from the pipe arm 18 by suitable insulating material shown at 22. I have shown a cable for carrying current at 23 mounted on an insulator 24 which insulator in turn is mounted on the pipe arm 18 back of the I-beam. This insulator is shown in Fig. 2 at 24 and the cables leading from the electrode 19 through this insulator 24 are indicated at 23. I have also shown two

other electrodes 25 and 26 to illustrate the arrangement of electrode cranes for a three phase furnace. The cables to these two other electrodes are shown at 27 and 28.

My present invention may be modified in various ways without getting away from the important improvements therein and I have found that it has special advantages in low construction cost and ample rigidity and simple operation. It also makes possible a simpler support for the electrode cables I have already referred to and it has every adjustment necessary for the proper alignment of electrode through the hole in the furnace roof.

Figs. 4 and 5 show one modification of my invention where a channel iron is used as the vertical beam. In these two figures a channel iron is shown at 41 and in Fig. 4 which is an elevation view I have shown rollers 42 and 43 and other rollers 48 and 46 below and above respectively on one side of the channel serving to keep it in vertical alignment. These rollers are seen in Fig. 5 at 52 and 50 on an axis 51. In this Fig. 5 is shown another roller 53 on an axis 54. Adjustment of these rollers will serve to keep the vertical beam from getting out of line to either side of its axis. In Fig. 4 I have shown a roller 45 below and a roller 49 above which serve as the guides for the beam in its movement up and down, the roller 49 being on the side of the electrode. I have also shown two other adjustable rollers, 57 below and 58 above, which serve to take up the currents so that there will be no tendency for the beam to move away from the electrode at its upper end. In the plan view shown in Fig. 5 these front and back rollers are shown at 55 and 56.

In Figs. 6 and 7 I have shown another modification of vertical movable beam in the shape of a T bar. In the plan view of Fig. 7 I have shown a roller 67 which may also be seen in the elevation view in Fig. 6 and I have also shown a roller on the front side or electrode side at 64 in both these views, and another roller 68 on the opposite sides of the main flange at the T bar on the same axis as the roller 64. These rollers together with the adjustable rollers 70 and 69 serve for the adjustment and alignment of the T bar in the plane of the electrode. To keep the vertical T beam in alignment so that it will not move from side to side I have provided rollers 63 and 66 above and below respectively.

My invention broadly covers any of these modifications of vertical beams and the means of keeping them in alignment.

In Fig. 1 I have shown an adjusting member 18^a which serves to adjust the position of the outwardly extending arm 18 above or below or on a horizontal line.

My improvement has many advantages

over the former construction, being much less expensive to build, also lighter and very easily adjustable and adapted for the carrying of the current conductors in an extremely simple and efficient manner.

What I claim is:

1. In combination, an electric furnace having a top adjustable electrode for arcing to the charge within the chamber of said furnace, and an electrode holder for said electrode, said holder comprising a vertical beam or mast and an outwardly extending arm mounted on the upper end of said beam, a clamping device on the outer end of said arm for holding the electrode, means for adjusting the effective length of said arm between the electrode and the beam, and means for raising and lowering the beam to regulate the height of the electrode with respect to the charge.
2. In combination, an electric furnace having a top adjustable electrode entering the chamber of said furnace from above, and an electrode holder comprising a vertical beam or mast mounted on one side of said furnace, an outwardly extending arm mounted on the upper end of said mast in an adjustable clamp whereby said arm may be moved in the direction of its axis and then held in adjusted position, and an electrode clamp on the outer end of said adjustable arm for carrying the electrode, and means for raising and lowering the mast to adjust the elevation of said electrode.
3. An electric furnace comprising a refractory chamber for an electrode to enter thru the top for arcing to the charge therein, and an electrode holding device, said device comprising a vertically movable member carrying an outwardly extending pipe arm held in a clamping device on said vertically movable member whereby the position of said pipe arm can be adjusted in or out from said clamping device to adjust the position of an electrode held in a holder mounted on said arm.
4. An electric furnace comprising a refractory chamber to be heated by current entering thru an electrode thru the top of said chamber, and an electrode holding device comprising a longitudinally adjustable pipe arm extending out horizontally from a vertically movable member, means for holding the pipe arm in adjusted position with respect to said holder, and an electrode holding member mounted on said arm.
5. An electric furnace comprising a refractory chamber adapted for using an adjustable electrode entering thru the roof thereof, and an electrode holding device comprising a vertical beam movable vertically in the direction of its axis, a bracket at the upper end of said beam, means for holding an outwardly extending arm therein whereby the effective length of said arm can be adjusted and an electrode holding device mounted on said arm to carry an electrode.
6. In an electric furnace, an electrode holder comprising a vertically movable vertical beam member mounted to move in line with its axis, an electrode holding arm mounted on the upper end of said beam and carrying an electrode, and rollers mounted on said furnace for engaging the surface of said beam to keep it in alignment, and means for adjusting the position of the roller axis of one or more of said rollers.
7. In an electric furnace, an electrode holder comprising a vertical beam movable in a line approximately parallel to its axis and having an outwardly extending arm mounted on its upper end whereby an electrode may be carried in a clamp mounted on said arm, rollers mounted on said furnace engaging the surface of said vertical beam, and means for adjusting the position of said rollers to hold the vertical beam in adjusted alignment around the axis of said vertical beam.

In witness whereof, I hereunto subscribe my name this 6 day of October, A. D. 1923.

ALBERT E. GREENE.
